LASTING MACHINE

Theodore P. Courchene, Beverly, Mass., assignor
to United Shoe Machinery Corporation, Flem-
ington, N. J., a corporation of New Jersey

Original application January 27, 1945, Serial No.
574,855. Divided and this application July 30,
1945, Serial No. 607,813

8 Claims. (Cl. 12—14)

1

This invention relates to lasting machines, the present application being a division of a copending application for Letters Patent for improvements in Lasting machines, Serial No. 574,855, filed on January 27, 1945. The invention is herein illustrated as applied to a machine constructed generally as disclosed in United States Letters Patent No. 1,843,232, granted on February 2, 1932, on an application of B. Jorgensen's, but modified in certain respects as further disclosed especially in Letters Patent No. 2,026,539, granted on January 7, 1936, and in Letters Patent No. 2,075,852, granted on April 6, 1937, on other applications of B. Jorgensen's. Machines of that character are frequently used, as herein shown, for lasting tennis shoes or the like which are commonly made on metal lasts and in which the uppers are secured to insoles by adhesion. It is to be understood, however, that the invention is not limited to the manufacture of shoes of that kind or, in some aspects, to machine organizations such as disclosed in the above-mentioned Letters Patent.

A machine such as that to which the invention is herein shown as applied is provided with toe-lasting means including a gripper which is closed by a treadle on the margin of the toe end of the upper prior to the starting of the power operation of the machine and serves thereafter to pull the upper in response to downward movement of the last effected by pressure applied to an insole on the last. The last with the upper and the insole thereon is mounted bottom upward on a toe rest and on a heel-end support which are movable downwardly with it; and also movable downwardly with the heel-end support is a member herein termed a heel carriage which is provided with a heel band for clamping the upper against the last about its heel end and, if the heel end of the shoe is to be lasted by the machine, with wipers for wiping the margin of that end of the upper inwardly over the insole. The heel carriage is held initially retracted lengthwise of the shoe by a latch which is moved by the operator to release it prior to the starting of the power operation of the machine, whereupon a spring acting on the carriage moves it to a definitely determined position to carry the heel band toward the shoe. In response to the movement of the carriage the heel-end support acts to move the shoe a short distance in the opposite direction to force it yieldingly against the heel band, the band serving as an abutment for positioning the last lengthwise relatively to the toe-lasting means by engagement with the heel end of the upper.

The above-mentioned heel-end support has been provided heretofore with a last pin arranged to enter the usual spindle hole in the heel end of the last when the work is presented to the machine. The locations of the spindle holes in dif-

ferent lasts frequently vary, especially when the lasts are made of metal, and this has sometimes delayed the operator in presenting the work since the inverted position of the last prevents him from seeing the spindle hole. To eliminate any such delay and thereby to increase the output of the machine, the invention provides a construction having no last pin but having means for otherwise controlling the last with respect to lengthwise movement. As herein shown, the heel-end support has a portion devoid of any last pin for engaging the top face of the heel end of the last and another portion arranged to engage the exterior of the last or of the upper thereon in a location between the heel-end portion and the toe-end portion of the last to hold the last against lengthwise displacement away from the heel band and thus to render the band properly effective to clamp the upper against the last and to determine the position of the last lengthwise relatively to the toe-lasting means.

The invention will now be more particularly described with reference to the accompanying drawings and thereafter pointed out in the claims.

In the drawings,

Fig. 1 is a view mainly in front elevation of the greater portion of the machine to which the invention is herein shown as applied, with the parts as they appear after the toe gripper has been closed and the heel carriage released prior to the starting of the machine;

Fig. 2 is a section, on an enlarged scale, on the line II—II of Fig. 1;

Fig. 3 is an enlarged view in front elevation of a portion of the structure shown in Fig. 1;

Fig. 4 is a view in front elevation of a portion of the heel-end support, with a part broken away and with one form of last and shoe thereon;

Fig. 5 is a plan view of the heel-end support shown in Fig. 4; and

Fig. 6 is a section on the line VI—VI of Fig. 5.

In view of the disclosures in the above-mentioned Letters Patent, only such portions of the machine as it is necessary to refer to for an understanding of the invention will be herein particularly described. The machine herein shown is constructed for lasting only the toe and heel ends of the shoe, the side-lasting mechanisms sometimes included heretofore in machines of the illustrative type being omitted.

For supporting the last and shoe the machine includes, as heretofore, a slide 2 movable downwardly against the resistance of a spring 4 by pressure applied on the bottom of the heel end of the shoe and a toe rest 6 movable downwardly against the resistance of a spring 8 by pressure applied on the bottom of the toe end of the shoe. The shoe and its supporting means are thus moved downwardly in the power operation of the

2

machine by a toe presser-foot 10 and a heel presser-foot 12 arranged to engage the toe and heel ends of the insole respectively. The toe presser-foot is supported on an arm 14 which by means of a handle 16 is swung forwardly by the operator to carry the toe presser-foot to a position over the toe end of the shoe, whereupon the machine is started and the arm is moved downwardly to carry the presser-foot into engagement with the insole and to impart to the toe end of the shoe its downward movement. As the toe presser-foot is thus moved downwardly the heel presser-foot is swung automatically to a position over the heel end of the shoe and is moved downwardly to depress that end of the shoe.

The toe-lasting mechanism includes a toe band 18 which embraces the upper about the toe end of the last and wipes the upper heightwise of the last in response to the downward movement of the last, and also includes toe-embracing wipers 20 which are thereafter operated to wipe the margin of the toe end of the upper inwardly over the insole into position to adhere to the insole. Further included in the toe-lasting mechanism is a toe gripper 22 which grips the marginal portion of the toe end of the upper and applies a pull to the upper in response to the downward movement of the last. This gripper, in accordance generally with the disclosure of Letters Patent No. 2,075,852, is closed on the upper prior to the starting of the power operation of the machine by a treadle 24 acting thereon through mechanism including a flexible cable 26.

As further described in Letters Patent No. 2,026,539, the above-mentioned vertically movable shoe support slide 2 carries at its upper end a slide 28 (Figs. 1 and 2) mounted for movements in directions lengthwise of the shoe along guideways 30 on the slide 2. Supported by the slide 28 is a vertical shoe-supporting rod 32 having thereon screw threads engaged by cooperating threads of a bevel gear 34 rotatably mounted on the slide 28. The bevel gear 34 is engaged by another bevel gear 36 fast on a shaft 38 which is rotatable in the slide 28 and extends through a slot 40 in the slide 2 to permit the movements of the slide 28 lengthwise of the shoe, the shaft 38 having thereon a hand wheel 42 for turning it to adjust the rod 32 vertically. Fast on the slide 2 are two horizontal rods 44 on which a heel carriage 46 is guided for movement lengthwise of the shoe, this heel carriage serving as a support for heel-lasting mechanism comprising wipers 48 (Fig. 1) for wiping the margin of the heel end of the upper inwardly over the insole and a heel band 50 for embracing and clamping the upper about the heel end of the last. To provide room for presenting the shoe to the machine the heel carriage 46 is held initially retracted lengthwise of the shoe by engagement of a latch member 52 (Figs. 1 and 3) with a lug 54 on the lower end of the carriage, and upon its release by the latch member the carriage is moved toward the shoe support by a spring 56 which abuts at its outer end against a bracket 58 fast on the rods 44. The latch member 52 is carried by a lever 60 which is pivotally mounted at 62 on the bracket 58 and is swung downwardly to release the heel carriage by means hereinafter described. The movement of the carriage toward the shoe is limited by its engagement with washers 64 (Fig. 2) mounted on the rods 44 and abutting against the slide 2. Substantially at the time when the carriage engages the washers the shoe is moved lengthwise into engagement with the heel band 50

50 by a short movement of the slide 28 toward the carriage 46 along the guideways 30. For controlling the slide 28 there is provided another slide 66 movable in directions lengthwise of the shoe along a guideway formed on a bracket 68 which is fast on the slide 2. Rotatably mounted in the slide 66 is a shaft 70 which carries a bevel gear 72 in engagement with another bevel gear 74 fast on a shaft 76 at right angles to the shaft 70 and also rotatably mounted in the slide 66. The shaft 76 is provided with screw threads engaging cooperating threads in a nut 78 mounted in a recess in the slide 28. On the shaft 70 is a hand wheel 80 for turning it. It will thus be seen that by turning this hand wheel the slide 28 may be adjusted in directions lengthwise of the shoe relatively to the slide 66, and that by the adjusting means the slide 28 and the slide 66 are held in fixed relation to each other so as to be movable as a unit in directions lengthwise of the shoe.

Pivottally connected at one end to a pin 82 in the slide 66 is a link 84 which is pivotally connected at its other end to a crank arm 86 (Fig. 1) fast on a shaft 88 mounted to turn in the bracket 58. On the hub of this crank arm are gear teeth in engagement with a pinion 90 which is fast on a shaft 92 also mounted to turn in the bracket 58. Fast on the shaft 92 is a depending arm 94 the lower end of which is in the path of the horizontally movable heel carriage 46. Accordingly, when the carriage is moved outwardly to its initial position where it is held by the latch member 52, as it is automatically near the end of the cycle of operations of the machine through connections including a chain 96 as heretofore, it acts through the arm 94, the pinion 90 and the crank arm 86 to move the link 84 toward the left (Fig. 1) and thereby to move the slide 66 and the shoe support slide 28 also to the left. In this manner the shoe is moved lengthwise in a direction away from the heel band 50 which is being moved in the opposite direction away from the shoe by the heel carriage. Such movement of the link 84 results in compression of a spring 98 held between a nut 100 on the link and a plate 102 on the bracket 68. The slide 66 and the connected slide 28 are held in the positions to which they are thus moved by the link 84 by means of a latch 104 pivotally mounted on the bracket 68 and controlled by a spring 106, this latch engaging a plate 108 on the slide 66. Accordingly, when the heel carriage 46 is released by the latch member 52 after the next shoe has been mounted on the shoe support, the slide 28 is held in its initial position by the latch 104 as the heel carriage is moved toward the shoe by the spring 56. When the carriage has nearly reached the position in which it is stopped by the washers 64, a screw 110 adjustably mounted in the lower end of the carriage engages a depending arm 112 of the latch 104 and causes the latch to release the slide 66. The spring 98 then acts through the link 84 to move the shoe support slide 28 toward the heel carriage until stopped by the engagement of the heel end of the shoe with the heel band 50. It will thus be seen that the position of each shoe lengthwise relatively to the toe-lasting means is determined by the heel band which acts as an abutment in contact with the heel-end face of the upper, the heel carriage 46 being always moved to the position determined by the washers 64.

The lever 60 which carries the latch member 52 is normally held up against the lug 54 on the heel carriage 46 by a spring 114 connected to a

rod 116 which is pivotally connected at its upper end to the lever. By means associated with the rod 116 and not herein fully disclosed, but described and claimed in application Serial No. 574,855 of which the present application is a division, the lever 60 is swung downwardly to release the heel carriage to the action of the spring 56 by further downward movement of the treadle 24 after the toe gripper 22 has been closed on the upper by the treadle.

The previously mentioned threaded rod 32 which serves as part of the means for supporting the heel-end portion of the last and shoe has formed on its upper end, as heretofore, a head 118 (Figs. 4 and 5) having therein a guideway 123 extending laterally of the shoe and curved about an axis extending lengthwise of the shoe in the vicinity of the bottom of its heel end, as more fully disclosed in Letters Patent No. 2,026,539, and mounted in this guideway for movement in one direction or the other laterally of the shoe to permit the bottoms of the toe ends of right and left shoes to be properly positioned relatively to the toe-lasting means is a block 122. This block has been provided heretofore with a last pin arranged to extend into the spindle hole in the heel end of the last. To save time in presenting a shoe to the machine, in view of the fact that such spindle holes are often not uniformly positioned in different lasts, there is provided for purposes of this invention, instead of such a last pin, a plate 124 secured by a rivet 126 on the top of the block 122 in a position further determined by a dowel pin 128. Mounted for adjusting movements along the plate 124 is another plate 130 arranged, as shown in Fig. 4, for supporting engagement with the top face of the heel end of the last and having at one end an upwardly extending portion 132 provided with a recess 134 having an inclined wall curved laterally of the shoe for engagement with the exterior of the last or of the upper thereon in a location between the toe-end portion and the heel-end portion of the last. The plate 130 is held in different adjusted positions, as may be required by shoes of different sizes, by a bar 136 (Fig. 6) and a screw 138 extending through the bar and threaded in the plate 124. The bar has at its opposite ends upraised portions engaging the opposite side portions of the plate 130 underneath, and when the screw 138 is tightened it acts through the bar to clamp the plate 130 against flanges 140 on the sides of the plate 124. It will thus be seen that in presenting a shoe to the machine the operator merely places the top of the heel end of the last on the plate 130 in the position illustrated in Fig. 4, and that when the slide 28 and the parts thereon are moved by the spring 98 toward the heel carriage 46, as hereinbefore described, the shoe is moved lengthwise toward the heel band 50 and is pressed against it by the upstanding portion 132 of the plate 130 which thereafter prevents its displacement away from the heel band. Accordingly, notwithstanding the absence of any last pin, the heel band is rendered effective to determine the position of the last lengthwise relatively to the toe-lasting means and to apply the required clamping pressure to the heel end of the upper in the lasting operation.

If the machine is used to last a shoe of the Oxford type mounted on a last of less height at its heel-end portion than that shown in Fig. 4, there is preferably utilized a block 142 (Fig. 1) for engaging and supporting the top face of the heel end of the last, this block being supported

on the plate 124 in the position determined by two pins 144 extending from the block into holes 146 (Fig. 5) in the plate. To provide room for the block 142 the plate 130 has in one end a curved recess 148 (Fig. 5). The block 142 may be detached when desired merely by lifting it off the plate 124. It will be understood that when the block 142 is used the upwardly extending portion 132 of the plate 130 performs the same function as when the block is not in use. It will further be understood that while this upwardly extending portion of the plate 130 will usually engage the upper, it may engage the last itself under some conditions.

As explained in Letters Patent No. 2,026,539, the purpose of movement of the block 122 along the curved guideway 120, when the block has been provided as heretofore with a last pin, has been to permit the block and the pin to assume positions in accordance with the lateral inclinations of the heel ends of right and left lasts when the lasts are tipped so that the bottom of their toe ends are positioned in proper relation to the plane of the toe wipers. In the construction herein shown, notwithstanding the omission of the last pin, provision for such movement of the block 122 is retained, so that the block and the plates 124 and 130 supported thereon similarly may assume different positions for right and left lasts when the lasts are of a style such as to require it. Since each last extends into the recess 134 in the upstanding portion 132 of the plate 130, the block and the plates may be readily moved in one direction or the other along the guideway 120 by the engagement of the shoe or last with the upstanding portion 132 as the work is presented to the machine. To limit adjustably their movements in opposite directions, there are provided stops 150 corresponding to similar stops shown in the last-mentioned Letters Patent, these stops in the construction herein shown being arranged to engage the sides of the plate 130. The stops are movable as heretofore along a guideway on the head 118 of the rod 32 and are adjusted equal distances toward or from each other by a rod 152 provided with right and left threads and having a knob 154 thereon for turning it. It will be understood that, if desired, the stops 150 may be so adjusted as to maintain the block 122 and the parts thereon in a central position.

In the use of the machine, in so far as it is of interest with reference to the present invention, the operator takes a shoe which, as herein shown, will usually have been already side lasted from its toe-end portion to its heel-end portion and mounts it on the toe rest 6 and the heel-end support. If the shoe is one of the Oxford type, as shown in Fig. 1, the block 142 will have been mounted on the plate 124 for engagement with the top face of the heel end of the last. Otherwise the top of the heel end of the last is engaged by the plate 130 as shown in Fig. 4. In thus presenting the work the operator positions it with a portion of the last, and usually also of the upper, in the recess 134 of the upstanding portion 132 of the plate 130 and by moving the heel end of the shoe laterally in one direction or the other, depending upon whether the shoe is a right or a left shoe, shifts the block 122 and the parts thereon to a position determined by engagement of one or the other of the stops 150 with the plate 130. In presenting the work the operator also positions the margin of the toe end 75 of the upper outspread in the toe gripper 22.

After the work has thus been properly presented the operator closes the toe gripper on the upper by depression of the treadle 24 and by further depression of the treadle thereafter swings the latch member 52 (Fig. 1) downwardly to release the heel carriage 46, whereupon the heel carriage is moved by the spring 56 to the position determined by its engagement with the washers 64 (Fig. 2), thus carrying the heel band 50 toward the shoe. Near the end of this movement of the heel carriage the latch 104 is operated to release the slide 28 to the action of the spring 98 which moves the slide and the parts thereon to carry the shoe toward the heel band and thus to cause the heel band properly to engage the heel end of the shoe. Such movement is imparted to the shoe by the engagement of the upstanding portion 132 of the plate 130 with the last or with the upper thereon, the operator at this time still holding the shoe down on the heel-end support with his hand. The operator then starts the power operation of the machine by swinging the arm 14 forwardly, and the machine lasts the toe and heel ends of the shoe in a manner which need not be described herein in view of the disclosures of the previously mentioned Letters Patent. It will be understood that after depression of the treadle 24 for the purposes above described the operator releases it to permit it to be returned to its initial position, the toe gripper being held closed on the upper by means disclosed in Letters Patent No. 2,075,852. Upon the release of the treadle the connections for controlling the heel carriage assume the positions in which they are shown in Fig. 1, so that upon return of the heel carriage and the slide 28 to their initial positions near the end of the cycle of operations they will be held by the latches 52 and 104, respectively.

Having described the invention, what I claim as new and desire to secure by Letters Patent of the United States is:

1. In a lasting machine, the combination with toe-lasting means, of an abutment for engaging the heel end of an upper on a last to position the last lengthwise relatively to said toe-lasting means, a toe rest for supporting the last at the top of the forepart, and a heel-end support for the last, said heel-end support having means for preventing lengthwise displacement of the last away from said abutment solely by engagement with the exterior of the last or of the upper thereon.

2. In a lasting machine, the combination with toe-lasting means, of an abutment for engaging the heel end of an upper on a last to position the last lengthwise relatively to said toe-lasting means, a toe rest for supporting the last at the top of the forepart, and a heel-end support for the last, said heel-end support being devoid of any last pin but having means for preventing lengthwise displacement of the last away from said abutment by engagement with the exterior of the last or of the upper thereon in a location between the heel-end portion and the toe-end portion of the last.

3. In a lasting machine, the combination with toe-lasting means, of an abutment for engaging the heel end of an upper on a last to position the last lengthwise relatively to said toe-lasting means, a toe rest for supporting the last at the top of the forepart, and a heel-end support for the last, said heel-end support being movable relatively to the toe rest to carry the last lengthwise toward said abutment and having means for pressing the last in that direction solely by

engagement with the exterior of the last or of the upper thereon.

4. In a lasting machine, the combination with lasting means including a heel band for embracing and clamping an upper about the heel end of a last, of a heel-end support for the last, and means for effecting relative movement of said heel band and heel-end support to engage the heel band with the upper, said heel-end support having means for engaging the top face of the heel end of the last and also means for preventing lengthwise displacement of the last away from said heel band solely by engagement with the exterior of the last or of the upper thereon.

5. In a lasting machine, the combination with lasting means including a heel band for embracing and clamping an upper about the heel end of a last, of a heel-end support for the last, and means for effecting relative movement of said heel band and heel-end support to engage the heel band with the upper, said heel-end support having means devoid of any last pin for engaging the top face of the heel end of the last and also means for engaging the exterior of the last or of the upper thereon in a location between the heel-end portion and the toe-end portion of the last to hold the last against lengthwise displacement away from said heel band.

6. In a lasting machine, the combination with lasting means including a heel band for embracing and clamping an upper about the heel end of a last, of a heel-end support for the last, and means for effecting relative movement of said heel band and heel-end support to engage the heel band with the upper, said heel-end support having a portion devoid of any last pin for engaging the top face of the heel end of the last and having also another portion extending heightwise of the last from said first-named portion and recessed to receive and engage the exterior of the last or of the upper thereon in a location nearer the toe end of the last than said top face and thereby to hold the last against lengthwise displacement away from said heel band.

7. In a lasting machine, an abutment arranged to be positioned opposite the heel-end face of a last to press against the heel end of an upper on the last, a heel-end support for the last, said heel-end support having means devoid of any last pin for engaging the top face of the heel end of the last and also means for engaging the exterior of the last or of the upper thereon in a location between the heel-end portion and the toe-end portion of the last to hold the last lengthwise against the pressure applied by said abutment, and spring means for effecting relative movement of said heel-end support and abutment to cause the abutment to apply its pressure to the upper.

8. In a lasting machine, an abutment arranged to be positioned opposite the heel-end face of a last to press against the heel end of an upper on the last, and a heel-end support for the last having detachable means devoid of any last pin for engaging the top face of the heel end of the last and other means also devoid of any last pin for engaging the top face of the heel end of a last of a different style when said first-named means is detached, said heel-end support being further provided with means for engaging the exterior of any last or of the upper thereon to hold the last lengthwise against the pressure applied by said abutment.

THEODORE P. COURCHENE.
